UNITED STATES PATENT OFFICE.

ANTON C. OLSON, OF MANDAN, NORTH DAKOTA.

LOCOMOTIVE CURTAIN.

1,421,293.

Specification of Letters Patent. Patented June 27, 1922.

Application filed October 18, 1920. Serial No. 417,836.

To all whom it may concern:

Be it known that I, ANTON C. OLSON, a citizen of the United States, residing at Mandan, in the county of Morton and State 5 of North Dakota, have invented new and useful Locomotive Curtains, of which the following is a specification.

This invention relates to a curtain for use between the cab of a locomotive and the 10 tank. Many fires have been started in locomotive cabs because, owing to the poor mounting of the side curtains, they have become ignited. Furthermore the side curtains when not in use have usually been located where they cover the back windows 15 of the cab, extend a foot or two below the apron, and cover the grab irons on the cab.

One of the objects of the present invention is to provide curtains which, when folded, 20 will be out of the way, are not likely to become ignited, and in no way interfere with the grab irons.

With the foregoing and other objects in view, which will appear as the description 25 proceeds, the invention resides in the combination and arrangement of parts and in the details of construction hereinafter described and claimed, it being understood that, within the scope of what is claimed, 30 changes in the precise embodiment of the invention shown can be made without departing from the spirit of the invention.

In the accompanying drawings the preferred form of the invention has been 35 shown.

In said drawings

Figure 1 is a side elevation of a portion of a cab and tank and showing a curtain supported in operative position.

40 Figure 2 is a section on line 2—2, Figure 1.

Figure 3 is a section on line 3—3, Figure 1.

Referring to the figures by characters of reference A designates a portion of a locomotive cab and B designates a portion of the tank. Suspended from the roof of the cab adjacent each side is a chain 1 provided with a ring 2 at its lower end into which is extended a finger 3 projecting from the looped end 4 of a rod 5.

Formed on the front portion of the tank B near each side is a metal box 6 and fastened within the upper portion of this box

is an eye bolt 7 which engages and supports 55 one end of the rod 5.

Secured within the box 6 is one edge of a curtain 8 and to the other edge of this curtain is fastened a curtain board 9 having laterally extending fingers 10. To the outer 60 face of the box 6 are secured superposed hooks or keepers 11 and when the curtain 8 is not in use it can be pushed back into the box 6 and the board 9 can be lowered so as to bring its fingers 10 into engagement 65 with the keepers 11. The board will thus act as a closure for the box and protect the curtain within the box from the elements and also from the torches, etc., carried about the locomotive. When the curtain 70 is to be used the fingers 10 are disengaged from the keepers 11, the curtain withdrawn from the box 6, and the fingers 10 lowered into engagement with keepers 12 secured to the back wall of the engine cab. 75 It is to be understood of course that the curtain has sliding engagement with the rod 5, there being rings 13 or the like on the curtain adapted to move along the rod.

A structure such as described has many 80 advantages over the curtains commonly employed. As the curtains are completely covered when not in use they are fully protected at those times from the weather and will thus last much longer than where the 85 curtains are constantly exposed. Curtains soon become saturated with oil and are easily ignited. As they are housed within the boxes when not in use, the torches carried by mechanics or helpers working on the engine will not ignite the curtains. The curtains are shorter than those ordinarily used and can, consequently, be made at less cost. As it is not necessary to remove the curtains between seasons, a considerable saving is effected by doing away with the help that would ordinarily be required to remove, 90 store, and replace the curtains. It will be noted furthermore that the curtains, when housed do not interfere with the view 100 through the back windows of the cab. Likewise they do not interfere with the grab irons which are thus left exposed at all times for use. As the curtains do not hang on the cab they do not obstruct the gang- 105 way between the cab and the tank.

What is claimed is:—

1. The combination with a cab structure

and a tank structure, of a supporting rod movably connected to the tank structure and extending across the space between said structures, a movable supporting connection 5 between the rod and the cab structure, a foldable curtain, slidable connections between the curtain and the rod, said connections being movable under the supporting connection.

10 2. The combination with a cab structure and a tank structure, of a supporting rod connected to one of the structures and bridging the space between both structures, one end of the rod being bent to provide a finger overhanging the rod, a movable supporting connection between the finger and one of the structures, a curtain, and means on the curtain for slidably engaging the rod and supporting the curtain throughout its 20 length, said means being movable under the finger and supporting connection.

3. The combination with a cab structure and a tank structure, of a rod connected to one of the structures and bridging the space 25 between the structures, said rod having a looped end and a terminal finger, the finger overhanging the rod, a detachable and movable connection between the finger and one

of the structures, and a curtain slidable on the rod and supported thereby throughout 30 its length.

4. The combination with a cab structure and a tank structure, of a housing on one of the structures, keepers carried thereby, keepers upon the other structure, a curtain 35 secured within and foldable into the housing, a member carried by the free end of the curtain and movable into engagement with either of the keepers to close the housing while the curtain is folded therein or to 40 hold the curtain extended across the space between the structures, a rod connected to one of the structures and bridging the space between the structures, a detachable, movable, supporting connection between the rod 45 and the other structure, and means slidable on the rod for supporting the curtain throughout its length when extended to close the space between the structures.

In testimony that I claim the foregoing as 50 my own, I have hereto affixed my signature in the presence of two witnesses.

ANTON C. OLSON.
